(57) CLAIM

The ornamental design for a cosmetic case, as shown and described.

DESCRIPTION

FIG. 1 is a top, plan view of my new design having a pull-out tray located in the base of the cosmetic case;

FIG. 2 is a front elevation view thereof;

FIG. 3 is a left side elevation view thereof;

FIG. 4 is a right side elevation view thereof;

FIG. 5 is a bottom plan view thereof;

FIG. 6 is a top, front and left perspective view thereof, showing the cosmetic case in an open condition with said tray pulled out from said base; and,

FIG. 7 is a top, front and left perspective view showing a second embodiment of my new design, said top plan, front elevation, left side elevation, right side elevation and bottom views being the same as the views described in FIGS. 1-5.
